TREATMENT OF HYDROCARBON OILS

Roland B. Day, Chicago, Ill., assignor to Universal Oil Products Company, Chicago, Ill., a corporation of Delaware

Application August 25, 1933, Serial No. 686,726

2 Claims. (Cl. 196—35)

This invention relates more particularly to the treatment of hydrocarbon oil distillates of motor fuel boiling range produced by the cracking of heavier and less valuable portions of petroleum oils though similar motor fuel fractions produced from other sources may also be treated such as those produced in the straight run distillation of crude petroleums or in the cracking of tars produced in the primary distillation of coals, shales, etc.

In a more specific sense the invention is concerned with a process which may be employed to controllably eliminate the undesirable constituents of primary or untreated motor fuel distillates, such constituents being classified generally as the gum-forming and colored compounds and the sulphur-containing derivatives, the latter imparting a bad odor to the distillates, and causing corrosion of the metal parts of automobile engines either before or after combustion.

In one specific embodiment the invention comprises the treatment of hydrocarbon oil distillates, particularly cracked hydrocarbon oil distillates of approximate motor fuel boiling range at elevated temperatures and pressures with hydrogen chloride and water in the presence of zinc-bearing clays.

The present invention is based on the discovery that certain types of zinc-bearing clays, particularly those obtained in the zinc-bearing regions of Missouri, may be successfully employed as catalytic materials in treating cracked distillates with hydrogen chloride and water for the removal of gum and color-forming and sulfur compounds. Treatments may be conducted either in vapor phase, mixed phase or substantially liquid phase at temperatures varying from approximately 200 to 600° F. and pressures of from atmospheric to 600 pounds per square inch, temperatures and pressures being inter-related so that optimum treating effects are obtained in any given case. As a general rule, however, best results are obtained in mixed phase treatments, that is, treatments in which there is some liquid and some vapor present in contact with the catalyst and the treating agents. The exact degree of vaporization of the oil under any given set of temperature and pressure conditions is difficult to determine on account of the presence of the vapors of water and hydrogen chloride which disturb the normal vapor-liquid ratio. However, by determining the liquid-vapor ratio of the stock undergoing treatment in separate laboratory test apparatus and introducing approximate corrections to eliminate the influence of the reagents it would appear that

as a general average the oil is about 25% vaporized. For most gasolines and naphthas which boil within the approximate range of 100 to 500° F. the best pressure range for treatments is approximately 100 to 200 pounds per square inch and the best temperature range is approximately 350 to 500° F. Obviously, when dealing with gasolines of widely varying chemical characteristics, particularly those from cracking operations upon different charging oils, the exact choice of conditions will be best based upon experiments in conjunction with tests upon the products. However, the ranges given are wide enough to include the majority of cases.

In regard to the zinc-bearing clays which are preferably used as solid contact materials, they vary somewhat in composition, particularly in respect to the total zinc content although the percentage of zinc in the clay as mined is generally of the order of from 20 to 25% by weight. The exact determination of the form of combination of the zinc is attended with the same difficulties encountered in determining the other components of clays, which can only be approximated in masses of such a complicated character. The composition and structure of clay minerals insofar as the same have been identified is usually determined upon relatively pure clays, and in the case of the materials of the present invention such a proximate analysis is attended with still greater difficulty and would be of problematical value.

It is probable that the zinc is combined partly as silicate and partly as oxide or hydrated oxide, corresponding generally to the form of combination of the other bases commonly present in clays such as aluminum, iron, calcium, magnesium and the alkali metals. The following analysis was made on a typical example of clay which gave good catalytic action.

Analysis of zinc-bearing clay

	Per cent	
SiO ₂	35.68	
Zn	23.40	45
Al	4.10	
Fe	2.67	
Undetermined	34.15	
Total	100.00	50

The undetermined portion consisted of water and oxides of the alkaline earth and alkali metals.

Both hydrogen chloride and water are essential for producing the treating effects according

to the process of the invention. To avoid confusion between the terms "hydrogen chloride" and "hydrochloric acid", the term "hydrogen chloride" within the meaning of the present specification is hereby stated to designate a dry gas having the chemical formula $HC1$, whereas "hydrochloric acid" designates an aqueous solution of this gas in water.

The presence of water is essential to the success of treatments conducted according to the present process although it may be added along with hydrogen chloride in different ways. As examples of alternative modes of procedure for assuring the presence of the required amounts of both hydrogen chloride and water in the treatments, the following alternatives are offered though they may not always produce equivalent treating effects:

1. Hydrogen chloride and water may be added from separate sources of supply; 2. Hydrogen chloride and steam may be added from different sources of supply; 3. Hydrochloric acid of regulated concentration may be added. As a general rule the last named method is the simplest in practice and usually is preferred over the other two.

30 While it has been definitely established in a number of cases that a definite degree of vaporization is best in refining treatments of the present character, the reasons for this are not entirely known. The primary object of all treatments upon unstable naphthas or gasolines containing unduly high percentages of sulphur and of gum-forming olefins is to reduce the sulfur to some 35 permissible limit and polymerize the more highly unsaturated olefins of a di- and tri- character while preserving the mono-olefins as anti-knock ingredients of the finished product. The selectivity of mixed phase treatments for accomplishing these ends is possibly connected in some way with the time factor and catalytic surface action, but the influences of these factors are so complicated that their exact analysis is impractical if not impossible.

45 A factor of importance is the presence of dissolved gases in stocks to be treated such as unstabilized pressure distillate; these gases tending to unduly increase the ratio of vapor to liquid phase and offset the desirable treating conditions. In some cases it may be best to stabilize the gasoline or naphtha prior to its subjection to the process in order to remove large amounts of dissolved gases such as hydrogen sulfide, methane, ethane, etc.

55 The nature of the reactions which have been found to produce the unusually good refining effects upon cracked gasolines when treated according to the invention is difficult of exact determination on account of the complex character 60 of the hydrocarbon distillates, particularly in regard to the chemical nature of the gum-forming compounds and the form of combination of the sulfur which is present. It may be assumed that 65 the gum-forming compounds consist, to a large extent, of di- and tri-olefins of a conjugated character since these compounds are known to readily undergo polymerization. The sulfur compounds may be mercaptans, sulfides, disulfides, 70 thioethers, thiophenes, etcetera, besides hydrogen sulfide.

The following equations are given to show the possible course of the essential reactions in the formation of readily removable polymers when 75 treating an olefin-containing distillate with hy-

drogen chloride and water in the presence of the zinc-bearing clay catalysts:

In the above equations hydrogen chloride is indicated as the active reagent, but it is to be borne in mind that a definite amount of water is always essential to effective treatment and that in this sense it functions as a true reagent since the quantities of water necessary for efficient treatment vary in different cases. Substantially no treating effects are produced when using dry hydrogen chloride, although minor effects may sometimes be noticeable on account of the presence of traces of moisture in the distillate undergoing treatment. The amount of water necessary is quite definite in any given case and it has been found that the addition of an excess above a certain minimum requirement is uniformly detrimental to the efficacy of the treatment.

To account for the extraordinary efficiency of the process in removing sulfur from cracked distillates which are refractory from the standpoint of ordinary sulfuric acid treatments, two types of reactions may be considered, the first involving polymerization of sulfur compounds along with the highly unsaturated hydrocarbons so that the sulfur appears in the heavy polymers and, second, those involving a preliminary combination of organic sulfur with a clay base, particularly zinc, to form sulfides which are later decomposed by hydrochloric acid to evolve hydrogen sulfide as a gas. These reactions are merely assumed and their proof would involve a series of difficult analyses which, if not impossible, would add little value to the present specification. Some evidence is at hand to show that combined sulfur in high sulfur oils appears after the treatment in mercaptans as a result of secondary reactions of hydrocarbons with hydrogen sulfide originally formed. However, with suitable precautions which will be developed in connection with a description of an operation, this tendency toward mercaptan formation can be minimized.

Usually only small amounts of hydrogen chloride are required in the treatments. According to the characteristic equations given above it is completely regenerated at the end of the polymerizing cycle so that the initial addition of some definite amount would suffice. However, certain small losses are unavoidable on account of its volatility which results in its being carried forward to the fractionating and condensing equipment of the treating apparatus. Such losses may be counterbalanced by the addition of equivalent amounts of acid, either from outside sources or recovered by absorption from the distillate receiver gases. 70

The process may be conducted in any suitable type of apparatus and Fig. 1 shows diagrammatically the essential features of a plant layout which can be used. 70

Distillates to be treated may be introduced to 75

the plant through line 1, containing control valve 2, and pumped by pump 3 through line 4, containing control valve 5, into and through heating element 6 disposed to receive heat from furnace 7. After being brought to a suitable temperature for treatment the heated products may be discharged through line 8, containing control valve 9 and leading to line 10. Hydrochloric acid in amount and concentration necessary for supplying the hydrogen chloride and water for the treatments may be supplied to pump 18 through line 16, containing control valve 17, the pump discharging by way of line 18, containing control valve 20, into line 10 where it mixes with the heated oils. As stated before, hydrogen chloride and water or steam may be separately introduced although means for this are not shown in the drawing.

The acid, water and oil pass under selected temperature and pressure conditions within the ranges previously mentioned through valve 11 and enter pressure treater 12 which contains a mass of zinc-bearing clay particles 13 dividing the interior of the treater into upper and lower spaces 14 and 15, respectively. During the passage of the oil and acid through the contact mass, degumming and desulfurizing reactions are effected and the products of the treatment pass through line 21, containing control valve 22, to fractionator 23, valve 22 being so manipulated in conjunction with valves subsequent to the fractionator that the pressure obtaining on the pressure treater is substantially reduced in the fractionator which may operate, for example, at pressures of from 50 to 100 pounds per square inch.

The plant shown in the drawing is designed for upward flow of oil and reagents over the clay particles but downflow treatments may also be used if greater benefits are obtained thereby. Higher boiling fractions than are desired in the finished gasoline appear in the fractionator as heavy polymer refluxes and comprise high boiling and substantially unaffected hydrocarbon fractions which may have been present in the raw naphtha if such was treated, and also polymers of olefins. Some sulfur may appear in the polymers in the case of high sulfur stocks and some of the original sulfur may be present in the fractionator in the form of hydrogen sulfide. It is frequently advantageous in the case of high sulfur oils to utilize treaters in series, the hydrogen sulfide formed in the treating reactions in the first of such a series being vented before further contact is brought about, thus reducing the tendency to metal sulfide formation with corresponding depreciation in the value of the contact materials. By venting the fixed gases and thus removing the majority of hydrogen sulfide the formation of mercaptans may be reduced to a practical minimum so that the desulfurization is more effective. Any hydrogen chloride which may be lost when the hydrogen sulfide and other low boiling hydrocarbons or fixed gases are released may be counterbalanced by further additions prior to the succeeding pressure treater. The vented gases may be passed through auxiliary beds of granulated metals and the chlorides and sulfides recovered if desired, or any other method of recovering the acid for further use or of getting rid of the hydrogen sulfide may be employed.

The refluxes from fractionator 23 may be removed through line 24, containing control valve 25 and disposed of in any suitable manner. In 75 case these refluxes are of fairly low sulfur content

and otherwise suitable, they may be used as recycle stock in the cracking plant which produced the naphtha or gasoline to be treated.

The vapors and fixed gases from the fractionator may be conducted through vapor line 26, containing control valve 27, and be cooled during passage through condenser 28, the cooled gases and condensed gasoline passing through rundown line 29, containing control valve 30, to receiver and separator 31 which has line 32, containing control valve 33 for the controlled release of fixed gases, a draw line 34, containing control valve 35, for the removal of the finished gasoline and a bottom draw line 36, containing control valve 37 for removal of water or aqueous solution which may accumulate in the receiver.

Obviously, to reduce corrosion troubles the portions of the plant which are subjected to contact with hydrochloric acid may be constructed of suitable acid-resisting materials.

The following examples of results obtained in commercial operations according to the present process are given to show its commercial value:

Example 1

The stock treated to produce a finished gasoline was a cracked gasoline produced from a West Texas residuum. This distillate was passed through a stationary body of zinc-bearing clay consisting of particles of from approximately 6 to 10 mesh at a temperature of approximately 450° F. and a pressure of 150 pounds per square inch. Water and hydrogen chloride were used at a rate corresponding to one pound per barrel of 40% hydrochloric acid. The following table shows the properties of the charging oil and the properties of the finished gasoline along with the losses encountered:

Properties	End pointed gasoline		40
	Untreated	Treated	
Gravity ° A. P. I.	55.5	55.0

¹ Equivalent to 2 hours noon June sunlight.

Example 2

The results shown in the following table were obtained in treating a pressure distillate produced from cracking an eastern paraffinic gas oil. The treating conditions were the same as in the previous example, to-wit, 450° F., 150 pounds pressure and one pound of 40% hydrochloric acid per barrel. The first two columns in 75

the table show the properties of the pressure distillate and the end point distillate producible therefrom by simple distillation without chemical treatment. The third column shows the properties of the product from the treatment which corresponds to the untreated end point distillate of column No. 2:

10	Properties	Pressure distillate	End-point distillate	
			Un-treated	Treated
15	Gravity °A.P.I.	52.8	54.5	55.7
	Color, saybolt		Yellow.	30 plus.
	Color stability ¹			27

	Percent bottoms	94.0	98.0	96.0
	Percent loss	2.0	1.0	1.0

¹ Equivalent to 2 hours' noon June sunlight.

It will be seen from the data presented in the two examples that a finished gasoline was produced with only moderate losses of the order of from 2 to 3%. The color and color stability were brought up to standard, the gums were markedly reduced along with a bomb stability increase, and the octane number was unaffected. 5

I claim as my invention:

1. A process for refining hydrocarbon oils of approximately motor fuel boiling range which 10 comprises treating the oil at a temperature between 200° F. and 600° F. with added aqueous hydrogen chloride in the presence of a natural zinc-bearing clay.

2. A process for refining hydrocarbon oils of 15 approximately motor fuel boiling range which comprises treating the oil with added aqueous hydrogen chloride in the presence of a natural zinc-bearing clay at a temperature of from 350° F. to 500° F. and under a pressure of from 100 20 to 200 pounds per square inch.

ROLAND B. DAY.
